UNITED STATES PATENT OFFICE.

JAMES FARDA, OF UTICA, NEW YORK.

DESIGN FOR A FUNERAL-WREATH.

52,786.

Specification for Design.

Patented Dec. 24, 1918.

Application filed December 8, 1917. Serial No. 206,355. Term of patent 3½ years.

To all whom it may concern:

Be it known that I, JAMES FARDA, a citizen of Italy, residing at Utica, in the county of Oneida and State of New York, have invented a new, original, and ornamental Design for a Funeral-Wreath, of which the following is a specification, reference being had to the accompanying drawings, forming part thereof.

The figure is a view of the funeral wreath as it appears over the door of a building.

I claim:

The ornamental design for a funeral wreath, as shown.

JAMES FARDA.
